TRIGGER LOCK FOR PISTOLS

John Quinn, Washington, D. C., and Lawrence
L. McDonie, Coral Hills, Md.

Application December 2, 1947, Serial No. 789,262

4 Claims. (Cl. 42—70)

(Granted under the act of March 3, 1883, as
amended April 30, 1928; 370 O. G. 757)

1

This invention relates to improvements in trigger locks for firearms, a specialized use thereof being in conjunction with automatic pistols although its principles could be employed in trigger locks for weapons of types other than pistols. For the purposes of this disclosure, the trigger lock is illustrated on what is known to persons familiar with small arms as the Colt automatic pistol, caliber .45, M1911 and M1911A1, the standard and current type of which has been responsible for serious accidents at times, due to the lack of a safeguard against the possibility of discharge of a cartridge occupying the bore in the absence of the magazine.

The presence of said cartridge can be the result of any of several contingencies. First, the user of the pistol may fail fully to count or may miscount the firing of the cartridges, thereupon to remove the magazine and omit to insert a refill, all the while being unaware of the possibility of there being a cartridge in the chamber of the barrel. Second, in the event of desiring to fire more than the magazine limit of seven cartridges at one loading, the slide is drawn back, a cartridge is inserted in the chamber of the barrel and the slide is allowed to close, but some distraction may divert the user from inserting the magazine and cause him to forget that the pistol is loaded and in condition to be fired. Third, a pistol subject to repairs may contain a jammed cartridge which could be fired by an inadvertent pulling of the trigger. Each of these cases is distinguished by the absence of a magazine from the magazine chamber, leading to a false sense of safety in handling the pistol.

As is readily understood from the foregoing premise, the supposedly unloaded pistol can be fired because there is no provision for locking the trigger in the absence of a magazine in the receiver. The latter circumstance might lead a person either holding or picking up the pistol to think that it were not loaded, thus prompting him to handle and accidentally to fire the pistol with the consequences already mentioned.

Therefore, it is proposed to equip the pistol with a safety device which automatically locks the trigger in its forwarded, i. e. safe position when the magazine is removed from the receiver. In addition to this facility, the invention has the important advantage of ready embodiment in the standard pistol identified above, with but a minimum of modification so that the cost involved in said modification, or the henceforth original manufacture of pistols embodying the improvement, is confined to a small and inconsequential

2

amount. The safety device weighs less than one ounce.

From these general statements it will be understood that one of the objects of the invention is to promote safety in the use of automatic types of small arms by automatically locking the trigger against manual operation whenever the magazine is removed.

Another object of the invention is to limit the requirement of modification of the particular type of pistol herein contemplated, or its equivalents, to a minimum of work and material.

Another object of the invention is to locate the trigger lock at a place of virtually immediate access, namely, against the left outer surface of the receiver and beneath the left stock or cover plate, so that the removal of the two stock or cover plate screws is the only requirement for reaching the single working part for its replacement in the event of a breakage, especially in the field.

Another object of the invention, and one influencing the adoption of the aforesaid location, is the emplacement of the lock on an external part of the receiver, thereby to avoid the necessity of involving the intricate internal mechanism in any manner, and with an important assurance, in the event of a breakage, against any of the pieces getting into said mechanism and jamming the pistol.

Other objects and advantages will appear in the following specification, reference being made to the accompanying drawings, in which:

Fig. 1 is a side elevation of a pistol, a portion of the left stock or cover plate being broken away to illustrate the emplacement of the trigger lock against the left and external surface of the receiver;

Fig. 2 is a vertical section taken substantially on the line 2—2 of Fig. 1, parts being shown in elevation, the trigger lock being displaced by the magazine;

Fig. 3 is a similar sectional view, illustrating the functioning of the trigger lock in the absence of the magazine;

Fig. 4 is a fractional perspective view of the grip portion of the pistol receiver, a part thereof being broken away;

Fig. 5 is a perspective view of the leaf spring which constitutes one of the important elements of the invention; and

Fig. 6 is a perspective view of the left stock or cover plate of the receiver.

Some of the characteristics of the known pistol 10 will be recognized as comprising the barrel (11,

the recoil-operated slide 12, the hammer 13, the receiver 14, the left and right stocks or cover plates 15 and 16, the magazine 17 and the trigger 18. The trigger bar 19 which is integral with the trigger, and which has the form of a rectangular loop (Fig. 4), is guided by the walls of parallel slots 23 in the confronting inner surfaces 21 of the receiver. The lateral depth of the slots and the thickness of the longitudinal members of the trigger bar are practically the same, so that they lie flush with the surfaces 21.

Openings 22 in the sides of the receiver 14 expose side portions of the magazine 17 when the latter is in place. The upper extremity of the standard magazine has inturned lips 23 which, in part, outline an orifice at the front of which the cartridges emerge. In addition to their function of retaining the cartridges until they are pushed out, one or the other of the two lips acts as a cam to release the trigger lock in the manner presently explained.

Lower and upper pairs of bushings 24 and 25 provide the mounts for the stocks 15 and 16. Only the lower bushing 24 on the left side enters into consideration herein, since the trigger lock is located on said side. It could be located on the right side. It is not required on both sides. Each of the bushings has a collar such as 26 on the lower left bushing, for the purpose of limiting the screwing of the bushings into the receiver. Screws 27 driven into the bushings secure the cover plates when emplaced on the bushings as shown. The inner faces of the cover plates are rabbeted at 28, usually for the purpose of conserving material. The rabbet in the left cover plate provides a convenient pocket in which the trigger lock is recessed for the major part of its length.

From this point on the description is addressed to the details of the invention, the main element of which consists of the leaf spring 29. This spring comprises a length of resilient metal which is formed with an initial bow as illustrated in Fig. 3. At its lower end it has a hole 30 which is large enough to fit freely upon the collar 26 of the lower left bushing 24. The bushing collar thus serves as the lower mount for the leaf spring.

At its upper end the leaf spring has locking and cam pins 31 and 32. They are spaced longitudinally of the leaf spring and are attached by riveting. The upper pin 31 which is the shorter of the two, occupies the component 33 of a hole in the receiver 14. Its beveled free end 34 is adapted to enter a complementary hole component 35 in the adjacent longitudinal member of the trigger bar 19 when registration of the hole components occurs in the forward or armed position of the trigger 18. The hole 33, 35 is an element of the invention, and is drilled through the parts named while the trigger is in the armed position. The locking of the trigger resulting from the projection of pin 31 into hole 35 happens only when the magazine 17 is absent from the magazine chamber or assumes a position therein sufficiently far below the cam pin 32 (Fig. 3) not to displace it from said chamber.

From this it will be seen that the pin 31 and its occupancy of the hole 33 provides the upper mount for the leaf spring. The latter is laid loosely against the left exterior of the receiver 14, being mounted upon the collar 26 and held in line by the insertion of the pin 31 in the hole 33. The cam pin 32 extends into the adjacent opening 22. The left stock or cover plate 15 has a recess 36 shaped to receive the lower extremity 75

of the leaf spring, and to fully contain that part of the leaf spring when the cover plate is clamped in place by the two cover plate screws against the side of the receiver.

Upon clamping the cover plate 15 down by the driving home of the screws 27, the initial bow (Fig. 5) in the spring 29 is effaced (Fig. 3) by the pressure of the bottom of the recess 36 against the spring. Thus the cover plate and its 10 securement to the receiver are used as the means whereby the inherently loose lock spring is clamped in place. This assembly is made while the magazine chamber is empty, the trigger 18 being in the forward or armed position which it normally assumes because of a spring (not shown) behind it. The spring being straightened, exerts an inward pressure which keeps it lying against the receiver, its upper pin 31 in locking engagement with the trigger bar and its cam pin 32 projected past the opening 22 into the magazine chamber.

This relationship is maintained as long as the magazine chamber remains empty. The trigger 18 cannot be pulled because its bar 19 is locked by the lock pin 31. Upon inserting either a loaded or empty magazine 17 into the chamber, the left lip 23 rides over the pin 32 (Fig. 2). The resulting cam action flexes the spring 29 outwardly, displacing the locking pin 31 from the hole in the trigger bar and releasing, that is unlocking, the trigger 18 for action.

In equipping a pistol with the invention, whether to modify current pistols or to embody it in newly manufactured ones, a jig will be used 35 for the accurate location of the holes 33 and 35. The bushings 24, 25 on the left side of the receiver are used as anchor points for the jig through which the drill is guided to center the holes on the vertical dimension of the nearest 40 member of the trigger bar with the trigger in the armed position.

This drilling of the receiver and trigger bar is accomplished after the mere laying aside of the left cover plate 15. The pistol need not be disassembled. None of the existing mechanism is affected otherwise than by the drilling of the one small hole simultaneously through the two parts. Access is had from the exterior, and should a breaking of the spring 29 occur, none 45 of the pieces can fall into the mechanism to jam the pistol. Such a breaking cannot render the pistol useless or even temporarily inoperative. The lower end remains clamped under the left stock. The upper end would be supported by 50 engagement of the lock pin with the rabbet in the stock and the hole in the receiver. Should there be any loose pieces they will fall out when the magazine is removed.

In the case of the foregoing breakage, it is 55 only the trigger lock that will have been disabled. A repair is easily made by simply removing the two left screws 27 and the left cover plate, whereupon a new safety device is loosely laid in place. One of its attachments is its mount on the lower bushing, the other mount being the engagement of its lock pin 31 with the wall of the hole in the receiver. The two mounts keep the lock spring in a permanent and established line from which it cannot deviate excepting by the foregoing remote chance of breakage.

The immunity of the pistol from damage due to the breakage of the trigger lock is in marked contrast with the potentialities of known devices for the same purpose. A review of the art most pertinent to the instant invention will disclose

a rather wide variety of locks which (1) require more or less extensive alteration or special construction of the parts with which the lock is concerned, (2) additionally require special construction of the lock itself and (3) are so situated in the internal workings of the weapon as to virtually make certain that jamming due to the lodgement of the parts in the mechanism would result from a breakage.

The invention herein described may be manufactured and used by or for the Government of the United States of America for governmental purposes without the payment of any royalties thereon or therefor.

We claim:

1. In a firearm equipped with a trigger bar slidable in a receiver having a magazine chamber and having a bushing projecting from an external surface of the receiver, said receiver having a hole registrable with a hole in the trigger bar in the armed position of the trigger, a cartridge magazine-operable trigger lock comprising an initially bowed leaf spring loosely emplaced against said surface, having a hole in one end fitting the bushing to provide one mount and having a locking pin at the other end occupying the receiver hole to provide a complementary mount, a stock clamped against the receiver, being set upon the bushing and over the contiguous part of the spring to efface its bow thereby to stress the spring and cause it to project the locking pin into the trigger bar hole, and a cam pin on the spring then extending into the necessarily vacant magazine chamber.

2. In a firearm equipped with a trigger bar slidable in a receiver having a magazine chamber and having a bushing projecting from an external surface of the receiver, a cartridge magazine-operable trigger lock comprising a leaf spring having a hole in one end and a locking pin at the other end, said leaf spring being supported in an undeviating position yet with inherent looseness by emplacement of the holed end over the bushing and the locking pin in the receiver-component of a hole transfixing the receiver and the trigger bar, a stock clamped against the receiver and spring to suspend its looseness and efface its bow thereby to hold it

under pressure to project the locking pin into the trigger bar hole in the absence of a magazine from the chamber, and a cam pin on the spring then permissibly extending into the chamber.

5 3. In a firearm having a cartridge receiver magazine chamber and a trigger bar slidable in the receiver, a trigger lock and means providing its mounting on an external and readily 10 accessible surface of the receiver, said means comprising at least one screw bushing extending from the lower portion of said surface and including a hole with components in the upper portion of the receiver and in a longitudinal 15 member of the trigger bar, said trigger lock comprising an initially bowed, inherently loose and separable spring having a hole in one end occupied by the bushing and providing one mount of a two-point attachment and at its 20 other end having a lock pin engaging the wall of the receiver hole-component providing the other mount, and a stock fitted on and secured to the bushing, being rabbeted to accommodate most of the spring and recessed to receive its 25 lower portion, the securement of the stock clamping the spring against the receiver and effacing its bow to project the lock pin through the trigger bar hole-component, and a cam pin extending from the spring into the chamber in the 30 path of an insertable magazine.

4. In a firearm having a cover plate, a holding bushing therefor, a spring constituting a component of a trigger lock for use in said firearm, said spring comprising a leaf having a hole in 35 one end to fit upon the bushing, and a pair of spaced pins at the other end of the spring, one pin being longer than the other pin to serve respectively as a cam actuatable by an insertable and removable magazine and as a trigger lock.
